Attorney.

UNITED STATES PATENT OFFICE

OSCAR ALVISTUR, OF OAKLAND, CALIFORNIA

APPARATUS FOR RELEASING GLIDER PLANES

Application filed December 13, 1929. Serial No. 413,852.

This invention relates to improvements in means for elevating the type of airplane known as gliders for the purpose of initiating the flight of the same.

5 The principal object of the invention is to provide an economically constructed and simply arranged apparatus whereby the glider can be elevated to the desired height and thereafter by a manipulation of a control cord or other actuating means the glider can be readily released to accomplish the desired gliding action.

10 A further object is to provide an apparatus that is positive in operation, durable and 15 one which can be readily and quickly manipulated.

Other objects and advantages will be apparent during the course of the following description.

20 In the accompanying drawings forming a part of this specification and in which like numerals are employed to designate like parts throughout the same,

The figure is a side elevation of the apparatus constructed in accordance with my invention and showing the same elevated in proximity to a captive balloon preparatory to impelling the glider into flight.

In the accompanying drawings wherein 30 for the purpose of illustration is shown a preferred embodiment of my invention, the numeral 6 designates a captive balloon which has depending therefrom a sheave or pulley 7 over which there is trained an endless cable

35 8 in turn connected to a second sheave or pulley 9 that is fastened to the ground in any convenient manner. The numeral 10 designates as a whole, the frame that serves as the medium for retaining thereon any type of glider 11.

40 This frame embodies in its construction a cross arm 12 that has connected thereto reinforcing bars 13 and 14. The frame is pivotally connected as at 15 to the front portion of the endless cable which portion of the cable, likewise beneath the point of pivotal connection, is received in slots or recesses formed in the wings 17 and 18 of the glider.

45 For the purpose of retaining the glider on the cross arm preparatory to the flight

of the same I employ on the top wing of the glider and centrally thereof, a pair of spaced vertical arms 19, each of which has mounted thereon a flange roller 20.

The numeral 21 designates a pull rope or 55 cable that is connected as at 22 to the cross arm 12, which cable is actuated by the occupant of the glider when he desires to initiate flight of the ship. It will be noted that the cross arm when actuated by the occupant 60 through the medium of the pull cable 21 will cause the cross arm to assume a substantially horizontal position to release the glider for flight.

The manner of raising the frame on the 65 endless cable 8 is obvious, for actuation of the cable either by means of a conventional wrench or other similar device will cause the cable to be reaved over the pulleys 7 and 9 and will convey the frame and glider thereon 70 to the desired height.

Assuming that the glider has been elevated to the position illustrated in the drawing, the operator then pulls the cable or control rope 75 21 and the frame will move from its full line position to the dotted line position, and the carrier wheels or rollers 20 traveling over the cross arm 12 will release the glider from the frame and initiate the flight of the plane.

Should it be desired to release a miniature 80 or toy glider or a glider that has no occupant therein the control cord could be readily lengthened to contact the ground and from this point actuation of the control cord will readily release the glider for flight.

85 It is to be understood that the form of my invention herewith shown and described is to be taken as a preferred example of the same and that various changes relative to the material, size, shape and arrangement of 90 parts may be resorted to without departing from the spirit of the invention or the scope of the subjoined claims.

Having thus described my invention, I 95 claim:

1. The combination with a captive balloon, of an apparatus for raising a glider plane to propel the glider into flight, said apparatus including an endless cable suspended from the balloon, and connected to the ground, a 100

glider carrying frame connected to said cable and adapted upon manual actuation to release the glider therefrom.

2. The combination with a captive balloon, an apparatus for elevating a glider plane to propel the same into flight, comprising an endless cable connected to the balloon, a glider carrying frame pivotally connected to said cable, and a control cable connected to said frame and under the control of the occupant of the glider for releasing the glider from said frame.
5. The combination with a captive balloon, of an apparatus for elevating a glider plane to propel the same into flight, said apparatus including means for elevating the balloon, a glider carrying frame mounted on said last mentioned means and adapted upon actuation of said frame by the occupant of the glider to propel the plane into flight.
10. The combination with a captive balloon, of an apparatus for raising a glider plane to propel the same into flight, said apparatus including means for elevating the balloon, a glider carrying frame mounted on said last mentioned means and adapted upon actuation of said frame by the occupant of the glider to propel the plane into flight.
15. The combination with a captive balloon, of an apparatus for elevating and lowering a glider plane, said apparatus including an endless cable connected to the balloon, and a glider carrying frame carried by said endless cable, and means carried by said frame for releasing the glider therefrom to propel the plane into flight.
20. The combination with a captive balloon, of an apparatus for elevating and lowering a glider plane, said apparatus including an endless cable connected to the balloon, and a glider carrying frame carried by said endless cable, and means carried by said frame for releasing the glider therefrom to propel the plane into flight.

In testimony whereof I affix my signature.

OSCAR ALVISTUR.
